To all whom it may concern:

Be it known that I, Josette E. Passarelli, a citizen of France and a resident of White Plains, county of Westchester, and State of New York, have invented a new, original, and ornamental Design for a Mitten, of which the following is a specification, reference being had to the accompanying drawing, forming a part thereof:

Figure 1 is a front perspective view of a mitten showing the new design, the rear view being the same;

Figure 2 is an elevational view of one side of the mitten, the other side being the same;

Figure 3 is a top plan view of the mitten as illustrated in Figure 2 but on a slightly larger scale; and

Figure 4 is a bottom plan view thereof.

I claim:

The ornamental design for a mitten, as shown and described.
